UNITED STATES PATENT OFFICE.

ROBERT F. LEMEN, OF EAST ST. LOUIS, ILLINOIS.

TOWEL-CABINET.

1,120,725.

Specification of Letters Patent. Patented Dec. 15, 1914.

Application filed March 15, 1913. Serial No. 754,580.

To all whom it may concern:

Be it known that I, ROBERT F. LEMEN, a citizen of the United States, residing at East St. Louis, in the county of St. Clair and

5 State of Illinois, have invented certain new and useful Improvements in Towel-Cabinets, of which the following is a specification.

My invention relates to that class of towel cabinets in which the towels are strung on 10 a rod.

The objects of the invention are to provide a cabinet of the rod type in which the towels may be locked within the cabinet, leaving one exposed for use; to provide the 15 rod with an offset exterior to the cabinet to support a towel in position for use; to provide an exterior extension of the rod leading from this towel supporting offset up along-side the cabinet into and across a top compartment so that the towel, when soiled, may 20 be moved up the rod and into said top chamber out of view; to provide the cabinet between its towel compartments with a shelf for comb, brush and soap. These objects I 25 accomplish by the construction shown in the accompanying drawing, in which:

Figure 1 is a perspective of a towel cabinet with my improvements applied thereto, the door being open. Fig. 2 is a front elevation of the cabinet with the towels in place. Fig. 3 is a perspective of the cabinet closed, and Fig. 4 shows one of the double or endless towels.

A designates the cabinet having a door A', 35 carrying a mirror. The cabinet has a top compartment B closed except at its top, which is left open, and the bottom b of this compartment is provided with ventilating openings b'. There is a shelf b² in the larger 40 lower clean-towel compartment C upon which may be placed various toilet articles.

D is the towel rod which extends from the right hand end of soiled-towel compartment B, to which it is fixedly secured, as at d, 45 across said compartment, out through an opening b³ and downwardly, as at d', along the exterior of the cabinet and under the bottom thereof, as at d², to an opening b⁴. The rod D then extends up through the 50 opening b⁴ in the clean-towel compartment C in the form of an inverted U. The free end of this U-shaped member is provided with a suitable fastening means, such as a padlock E.

F designates the towels, which are endless 55 like roller towels. Each towel has an eyelet or grommet f extending through both layers or folds.

In operation the free end of the rod D is swung out and the clean towels are strung 60 thereon, as shown in Fig. 2, say a week's supply. A towel is moved along the rod D until it rests upon the supporting offset d' thereof, where it will hang ready for use. When soiled, the towel will be moved up on 65 the rod and inwardly thereon into the top compartment B, where the soiled towels will be out of sight, though exposed to the air.

The door must be unlocked by some one 70 in authority every time a clean towel is to be brought into use and thus wastefulness is checked and unauthorized persons prevented from gaining access to the clean supply.

While I have shown the double towels, 75 single towels may, of course, be used.

What I claim is:

1. A towel cabinet provided with a lower compartment for clean towels, an upper compartment for soiled towels, a rod secured at 80 one end in the upper compartment extending thence downwardly along the exterior of the cabinet, thence laterally under the cabinet to form a towel support, and thence upwardly into the lower compartment to 85 receive the clean towels.

2. A towel cabinet provided with an upper compartment open at its upper side, a lower compartment open at its front, an opening being formed in the bottom of the lower 90 compartment and another opening in one end of the upper compartment, a rod secured at one end in the end of the top compartment and extending across said compartment and out through its end opening, 95 thence down alongside the cabinet, thence laterally under the cabinet to form a towel supporting offset, and thence up through the bottom opening and formed within the lower compartment with a U-shaped member, the free end of which extends down to the bottom thereof, and a door closing the lower compartment.

3. A towel cabinet comprising an upper open top compartment for soiled towels, a 100 lower open front compartment for clean towels having a recess in the front edge of one of its walls, a door closing the lower

compartment and also closing said recess, and a towel rod secured at its upper end in the upper compartment and extending thence downwardly exterior to the cabinet and through said edge recess into the lower compartment to receive a pile of clean towels; whereby the towels may only be moved along the rod and through the recess for suspen-

sion on the rod exterior to the cabinet by first opening the door.

In testimony whereof I affix my signature in presence of two witnesses.

ROBERT F. LEMEN.
